UNITED STATES PATENT OFFICE.

ALBERT MAKOWSKI, OF MERIDEN, CONNECTICUT.

SPIRIT-LEVEL.

1,018,719.

Specification of Letters Patent. Patented Feb. 27, 1912.

Application filed August 18, 1911. Serial No. 644,759.

To all whom it may concern:

Be it known that I, ALBERT MAKOWSKI, a subject of the Emperor of Austria-Hungary, residing at Meriden, in the county of 5 New Haven and State of Connecticut, have invented a new and useful Improvement in Spirit-Levels; and I do hereby declare the following, when taken in connection with the accompanying drawings and the letters 10 of reference marked thereon, to be a full, clear, and exact description of the same, and which said drawings constitute part of this specification, and represent, in—

Figure 1 a perspective view of a spirit 15 level constructed in accordance with my invention. Fig. 2 a side view of the same showing an electric lamp attached thereto. Fig. 3 a plan view on an enlarged scale, of a section of the level with a bracket attached 20 thereto and the lamp engaged with the bracket. Fig. 4 a sectional view illustrating the engagement of the fingers of the lamp with the bracket.

This invention relates to an improvement 25 in spirit levels such as commonly used by carpenters and masons, and which usually consist of a rectangular block or frame with a bubble tube in one edge for use horizontally, and a bubble tube arranged in an 30 opening in the body of the block for vertical use. As these levels are frequently used in dark places, it is desirable to illuminate the bubbles; and the object of this invention is to provide simple means whereby an 35 electric light may be conveniently detachably connected with the level in position to illuminate either bubble; and the invention consists in the construction hereinafter described and particularly recited in the claim.

40 In carrying out my invention I employ the usual level block 2 having a bubble tube 3 arranged in the edge 4, and with the usual side opening 5 in which is a second bubble tube 6. The edges of the block adjacent to 45 the bubble tube 3 are usually cut away to allow light to reach the bubble tube, and in one side of the block adjacent to the light-opening 7 I attach a bracket 8 which is

formed with two outwardly projecting arms 9, 10, the inner faces of which are formed 50 with recesses 11, and the face of the bracket between the arms has an inclined wall 12 for the purpose as will hereinafter appear. In addition to placing the bracket adjacent to the bubble tube 3 I preferably locate one 55 of these brackets on each side of the block adjacent to the bubble tube 6. In connection with a bracket thus described, I employ a small electric lamp 13 which is substantially 60 like a pocket lamp, which has a push button 14 in one side by which the circuit through the batteries inclosed in the case is closed. Attached to this lamp casing 13 on opposite sides are spring fingers 15 and 16 which project beyond the end of the casing, 65 thence inward and outward, and each carries a pin or projection 17 which engage with the notches 11 in the bracket. The outer ends of the fingers 15 and 16 have angular edges 18 which co-act with the beveled wall 70 12 of the bracket and in such a way as to cause the ends of the fingers to interlock with the bracket.

To attach the light to the level the fingers are crowded together and the pins 17 entered into the recesses 11 and the lamp will stand at an angle to the body of the level so as to throw light from the bulb 19 on the bubble tube. To light the lamp it is only necessary to move it slightly to one side so 80 as to cause the finger 15 to crowd the push button 14 inward, and when moved to this position the friction of the ends of the fingers on the bracket will cause the lamp to maintain this closed position so as to maintain the light. When not required, the simple movement of the lamp in the opposite direction will release the tension of the fingers with relation to the bracket and allow the finger 15 to move away from the push 90 button 14 to such an extent as to break connection through the lamp. For convenience one end of the body 2 will be formed with a recess or pocket 20 to receive the lamp and this pocket may be closed by a cover 21. 95 When not required for use the lamp will re-

main in the pocket from which it can be conveniently removed and connected with one or the other of the brackets when necessary.

5 I claim:—

The combination with a level having a bubble tube, and bubble sight-opening, of a bracket arranged adjacent to the said bubble sight-opening, and an incandescent elec-

tric lamp provided with fingers detachably connected with said bracket.

In testimony whereof, I have signed this specification in the presence of two subscribing witnesses.

ALBERT MAKOWSKI.
